UNITED STATES PATENT OFFICE.

LOUIS A. KRAMER, OF CHICAGO, ILLINOIS.

HOG-DEHAIRING MACHINE.

1,276,546.

Specification of Letters Patent. Patented Aug. 20, 1918.

Application filed June 22, 1917. Serial No. 176,264.

To all whom it may concern:

Be it known that I, LOUIS A. KRAMER, a citizen of the United States, residing at Chicago, in the county of Cook and State of Illinois, have invented certain new and useful Improvements in Hog-Dehairing Machines; and I do hereby declare the following to be a full, clear, and exact description of the invention, such as will enable others skilled in the art to which it appertains to make and use the same.

My invention relates to carcass-dehairing machines of the general class commonly used for the dehairing and cleaning of hogs, its general objects being to provide an unusually positive and efficient machine and one which will occupy a small amount of floor space in proportion to its output. In my copending application filed May 19, 1917, as Serial No. 169655 I have shown and described a hog-dehairing and scraping machine in which the hogs are scraped by rotating scraper-carrying members while the hogs rest freely upon chain conveyers. While possessing a high output, this type of machine requires a much larger floor space than some of the older types of dehairing machines, so that it cannot readily be substituted for the latter without expensive alterations in the buildings or without the providing of additional ground space; and where ground rents are high, the said type of my copending application is likewise objectionable because of the space thus occupied. Moreover, since scrapers of my previous machine can operate on only one hog at a time, the capacity of this machine cannot be increased by the simultaneous or overlapping conveying of a number of hogs into the path of each beater. So also, since each hog is separately sprayed, the amount of water required for the rinsing (and hence the power for pumping the same) is higher than it would be if the same rinsing water was used successively on a number of hogs before reaching the hair-separating screen.

In my present invention, I have aimed to overcome these objections by providing a machine which will occupy relatively small floor space and which therefore may easily be substituted for various older types of machines having a much smaller output; which will convey hogs past the same beater or scraper elements in a number of paths, thereby increasing the output; and which will use the same rinsing water successively

upon the relatively clean hogs and the less cleaned hogs following the same. Furthermore, my invention aims to provide a hog-dehairing machine in which the dirt, scarf skin and hair are all removed from the hogs while the latter are freely suspended and gradually rotated, and in which all of this cleaning is effected by beating and scraping elements carried by a single shaft. So also, my invention aims to provide a machine which will take a hog from a scalding tub on one floor past a series of beaters and through rinsing means, and which will automatically deliver it on another floor. Further objects of my invention are to provide a single vertical shaft carrying all of the beater and scraper elements and also carrying means for rotating the hogs; to provide means for limiting the movement of each hog both radially outward of the shaft and in other directions; to provide simple and effective means for separating the hair from the rinsing water, and simple means for preventing an accidentally detached hog from damaging the hair-separating mechanism; to provide a simple and positive drive for the beating, hair-separating and hog-conveying mechanism, and to provide simple mechanism for conveying the hogs.

Still other objects will appear hereafter.

Figure 1 is a central longitudinal section through the main portion of a machine embodying the same, with certain portions broken away.

Fig. 2 is a transverse section taken along the line 2-2 of Fig. 1.

Fig. 3 is a similar section taken along the line 3-3.

Fig. 4 is a side elevation of the machine with portions of the housing omitted.

Fig. 5 is an enlarged vertical section through a portion of the housing, with the shaft and the elements carried thereby omitted, showing the method of automatically delivering the hogs to the delivery rails.

Fig. 6 is a horizontal section taken along the line 6-6 of Fig. 1.

Fig. 7 is a detail of one of the conveyor chains, showing one of the studs for receiving the hog-holding hooks.

Fig. 8 is a fragmentary view of a twin-swivel hook suitable for use with the machine of my invention.

Fig. 9 is a transverse plan view of the casting showing the co-action of the beaters and the webs.

In accomplishing the purposes of my invention according to the embodiment of the accompanying drawings, I employ a vertical shaft 1 carrying a plurality of flexible vanes 2 each equipped with metal scrapers 3, these vanes being spaced longitudinally along the shaft and being shown as secured to drums 4 mounted on the shaft and each drum having radially enlarged end flanges 5. The shaft 1 is guided at its upper end by a bearing 6 formed in the top 7 of a substantially cylindrical casing 8, while the weight of the shaft and of the elements carried by the latter is born by a thrust bearing 9, which bearing is desirably equipped with screws for raising or lowering the bearing plate and shaft to insure the proper meshing of the bevel gears hereafter mentioned. The shaft 1 is driven from power applied to a pulley 10 through a drive shaft 11 and bevel gears 12, and the shaft 1 in turn carries a worm 13 for driving a worm wheel 14 on a sprocket shaft 15. This latter shaft carries two sprockets 16 meshing respectively with two endless chains 17, each of which chains desirably is equipped at intervals with projecting pins 18. Each of the chains 17 passes over idler wheels causing it to pass from one of the drive sprockets 16 to a point above the water 19 in a scalding tank 20, thence into the casing 8 and up along the innerface of the latter to an upper idler 21 disposed adjacent to an inclined delivery rail 22. The upwardly extending portions of the two chains 17 desirably are disposed diametrically opposite the shaft 1, and the two delivery rails 22 preferably lead to a single delivery table 23.

Below the guide pulleys 24 at the lower ends of the vertical stretches of chain and surrounding the shaft 1 is a water chamber 25, covered by a conical screen or sieve 26, the top of which sieve is continuously swept by a vane or rake 27 fastened to the shaft 1 and rotating with the latter. The water chamber 25 is connected by piping to a pump 28, which pump forces the water through a riser pipe 29 into a spray pipe 30, the latter being desirably disposed in ring shape near the top of the casing 8.

In using the machine thus described, the above described pump, shafting and endless chains are maintained continuously in operation, and each hog as it reaches the machine end of the scalding tank 20 is suitably gripped and attached to one of the chains 17, as by catching the lower end of the twin swivel hook 31 in one hind leg of the hog 32 and hooking one of the upper twin bends over the shank of one of the pins or studs 18. When thus hooked, the hog is dragged by the chain into the interior of the casing 8 and slowly raised within the latter, thus bringing it into the path of one after an-

other of the successively higher beating or scraping members. Being suspended from a hook with a swivel 32 at its center, the hog is free to turn, hence the beaters while forcing the hog away from the shaft and 70 against the interior of the casing 1 will gradually rotate the hog so as to expose all surface portions of the latter to the action of the scrapers. To facilitate this turning, I also provide collars or flanges 5 fast upon 75 the shaft, which collars engage the hog whenever the latter swings radially inward toward the latter, and which collars therefore tend to rotate the hog. So also, I preferably equip the bore of the casing 8 80 with inwardly directed fins or webs 33 placed at opposite sides of each chain 17 and adapted to limit the swinging of the hog in those directions, thereby momentarily stopping the swinging of the hog while 85 permitting the scrapers to act upon it. Thus, each hog as it is gradually raised, swings, turns, and pauses as far as its horizontal movements go, while permitting one after another of the beating and scraping 90 members to act upon it.

Meanwhile, the water issuing from the spray nozzle 30 strikes the uppermost hog, together with the upper portions of the casing and of the puffs rotating within the 95 latter, and then trickles and splashes downward, successively striking one after another of the consecutively ascending hogs, and thus rinsing the detached hair and other particles off the hogs. These particles fall 100 upon the conical sieve or screen 26 and are swept off the latter by the vane or rake 27 into a hair outlet 34, while the water trickles through into the chamber 25 and is again pumped from the latter up to the spray nozzle 30. To prevent the hogs from striking the sieve 26 and any deposit on the latter, either while the hogs are being dragged into the casing or in case one should accidentally fall, I provide a guard 35 of any suitable 110 type above the rake 27. To detach the hogs at the upper end of their travel, I preferably curve each delivery rail 22 at its upper end so that this rail will engage the free prong of the duplex end of the swivel hook supporting the hog, thus releasing the other prong from the pin 18 on the chain and transferring the load of the hog to the delivery rail.

Thus it will be evident that from the time 120 the swivel hook is manually applied to both the hog and the pin on the chain, the action is entirely automatic until the hog slides down one of the delivery rails within easy reach of the men at the delivery table 23; 125 also, that the rinsing will be both economical and effective, since the water is used over and over, and since the fresh water first strikes the uppermost or most nearly clean hogs. Moreover, by suitably proportioning 130

the distances between the shaft and the casing, and between the webs 33 and the vertical riser portion of each chain, I can easily afford such a resistance to the thrust of the 5 scraper-carrying members 2 as will enable the scrapers 3 upon the latter to work effectively, thus removing not only the hair but also the scurf skin and the black dirt and preparing the skin for the pickling. At the 10 same time, the swiveling of the hog upon its support will permit it to rotate about an approximately longitudinal axis, and the flanges 5 coöperate with the members 2 and 3 in compelling the hog to rotate, so that no 15 portion of its skin can escape the treatment. By using two chains, I can keep one man busy attaching the hogs alternately to one and the other of the chains, thus keeping all of the beating and scraping elements con- 20 tinuously busy and thereby securing a high hourly output for the machine. So also, since the rotating elements 2 keep striking the dripping water, they will splash this against the hogs both directly and by reflec- 25 tion from the wall of the casing 8, so that I secure the effect of a forcible spraying without requiring a high pressure pump. At the same time, it will be obvious that by mounting all of the rotating beating and 30 scraping elements on the single vertical shaft, I not only simplify the mechanism greatly as compared with that of former constructions, but also reduce the floor space. Consequently, I am able to build a machine 35 which may readily be installed in place of existing machines of old types, and which affords a greatly increased output with relatively little cost for attendance and power.

Moreover, it will be evident from Fig. 9 40 that the skin-treating elements will be pressed more firmly against large hogs than against small ones, thereby automatically compensating for the differences in size without requiring any sorting of sizes, 45 changes in speed, or stopping and starting of the machine. In other words, the hogs when taken just as they happen to come will be positively and automatically fed through the machine, scraped and rinsed while in 50 transit, and automatically fed upon the delivery rails.

However, while I have pictured my invention in an embodiment having just two conveyer chains and having the hogs suspended 55 by three-pronged hooks, I do not wish to be limited to these or other details of the construction and arrangement here disclosed, it being obvious that the same might be modified in many ways without departing from 60 the spirit of my invention.

I claim as my invention:

1. In a hog dehairing machine, a shaft, a 65 plurality of scraper members carried by the shaft and distributed longitudinally there- of, means for rotating the shaft, and means

for conveying hogs past all the scraper members in a plurality of separate paths parallel to the axis of the shaft and symmetrical with respect to the shaft, thereby balancing the strains on the shaft. 70

2. In a hog dehairing machine as per claim 1, means associated with the conveying means for permitting each hog to rotate about an axis substantially parallel to the axis of the shaft. 75

3. In a hog dehairing machine as per claim 1, means carried by the shaft and operating independently of the scraper members for rotating the hogs traversing all of the said paths. 80

4. In a hog dehairing machine as per claim 1, means carried by the shaft and operating independently of the scraper member for rotating the hogs traversing all of the said paths, the said means being disposed between the consecutive scraper members carried by the shaft. 85

5. In a hog dehairing machine as per claim 1, collars on the shaft adapted to engage the hogs and to rotate the hogs by frictional engagement with the latter. 90

6. In a hog dehairing machine, a rotating shaft, a plurality of scraper members carried by the shaft and spaced longitudinally thereon, means independent of gravity for conveying a hog in a path substantially parallel with the axis of the shaft and past all the said scraper members, and immovable means for limiting the movement of the hog in directions radially outward from said axis. 95

7. In a hog dehairing machine, a rotating shaft, a plurality of scraper members carried by the shaft and spaced longitudinally thereon, means independent of gravity for conveying a hog in a path substantially parallel with the axis of the shaft and past all the said scraper members, and immovable means for limiting the movement of the hog in a plurality of directions. 105 110

8. In a hog dehairing machine, a rotating shaft, a plurality of scraper members carried by the shaft and spaced longitudinally thereon, means independent of gravity for conveying a hog in a path substantially 115 parallel with the axis of the shaft and past all the said scraper members, and a substantially cylindrical immovable casing coaxial with the shaft and disposed for limiting the movement of the hog radially outward from the axis of the shaft. 120

9. In a hog dehairing machine, a rotating shaft, a plurality of scraper members carried by the shaft and spaced longitudinally thereon, means independent of gravity for conveying a hog in a path substantially parallel with the axis of the shaft and past all the said scraper members, and a substantially cylindrical casing coaxial with the shaft and disposed for limiting the 125 130

movement of the hog radially outward from the axis of the shaft, and a web on the interior of the casing extending in a plane substantially radial of the axis of the shaft and disposed for limiting the movement of the hog circumferentially within the casing.

10. In a hog scraping machine, a vertical shaft, carrying the scraping elements, means for conveying hogs upwardly in operative relation to the scraping elements, a substantially conical screen surrounding the shaft below the scraping elements, and a vane carried by the shaft and disposed for removing matter deposited on the screen.

11. In a hog scraping machine arranged as per claim 10, a casing housing the scraping elements and the screen and having an opening adjacent to the screen as an outlet for the matter removed from the screen by the vane.

12. In a hog dehairing machine, a rotating shaft, scraper members carried thereby and spaced longitudinally thereon, means for conveying a hog in a path substantially parallel with the axis of the shaft and past all of the said scraper members, and means operatively independent of the hog conveying means for limiting the movement of the hog in directions radially outward from the said axis.

13. In a hog dehairing machine, a substantially vertical rotating shaft, scraper members carried by the shaft and distributed longitudinally thereof, and vertically disposed conveyer means arranged for freely suspending hogs and successively con-

veying them past all of the scraper members.

14. In a hog dehairing machine as per claim 13, means carried by the shaft and operating independently of the scraper members for rotating the hogs while they are being conveyed.

15. In a hog dehairing machine as per claim 13, means carried by the shaft between successive scraper members and operating independently of the scraper members for rotating the hogs while the latter are being conveyed.

16. In a hog dehairing machine as per claim 13, collars fast upon the shaft and disposed for rotating the hogs by frictional engagement with the latter.

17. In a hog dehairing machine, a substantially vertical rotating shaft, scraper members carried thereby and distributed longitudinally thereof, a casing substantially concentric with the shaft, and vertically moving conveyer means arranged for freely suspending hogs.

18. In a hog dehairing machine as per claim 17, webs projecting inward from the casing and coacting with the latter to limit the swinging movement of the suspended hogs.

19. In a hog dehairing machine as per claim 17, means carried by the shaft and disposed for rotating the suspended hogs, and means carried by the casing for resisting such rotation.

Signed at Chicago, June 16th, 1917.
LOUIS A. KRAMER.
